UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

DESIGN FOR A CLAMP PLATE.

Application filed September 9, 1927. Serial No. 23,339. Term of patent 14 years.

To all whom it may concern:

Be it known that I, HERBERT S. JANDUS, a citizen of the United States, residing at Detroit, in the county of Wayne and State of Michigan, have invented a new, original, and ornamental design for a Clamp Plate, of which the following is a specification, reference being had to the accompanying drawing, forming part thereof, wherein—

Fig. 1 represents a front elevation and Fig. 2 a side elevation of a clamp plate exhibiting my new design and adapted to be used on a vehicle bumper.

I claim:—

The ornamental design for a clamp plate, substantially as shown.

HERBERT S. JANDUS.
